[57] CLAIM

The ornamental design for a page finder with top and bottom insert pockets, as shown and described.

DESCRIPTION

FIG. 1 is frontal view of a page finder with top and bottom insert pockets;

FIG. 2 is rear view thereof;

FIG. 3 is a left perspective view thereof; and,

FIG. 4 is a right perspective view thereof, showing an insert depicted in broken lines for illustrative purposes only, not forming a part of the claimed design.
